UNITED STATES PATENT OFFICE.

HENRY LOTZ, OF PROVIDENCE, RHODE ISLAND, ASSIGNOR TO THE LOTZ PROTECTOR AND SALVAGE COMPANY, OF PROVIDENCE, RHODE ISLAND, A CORPORATION OF RHODE ISLAND.

DEVICE FOR HOISTING SAFES FROM SUNKEN VESSELS.

1,236,956.

Specification of Letters Patent. Patented Aug. 14, 1917.

Application filed December 23, 1916. Serial No. 138,551.

To all whom it may concern:

Be it known that I, HENRY LOTZ, a subject of the Czar of Russia, residing at Providence, in the county of Providence and State of Rhode Island, have invented certain new and useful Improvements in Devices for Hoisting Safes from Sunken Vessels; and I do hereby declare the following to be a full, clear, and exact description of the invention, such as will enable others skilled in the art to which it appertains to make and use the same.

The invention relates to a device for hoisting safes from sunken vessels.

The object of the present invention is to provide a simple, practical and efficient device adapted to enable a salvage line to be readily connected to the safe of a sunken vessel for the hoisting of the safe from the vessel.

A further object of the invention is to provide a device of this character adapted in event of the breakage of a hoisting rope or cable to permit another to be readily connected to the safe to be removed and capable also of permitting a plurality of lines to be simultaneously coupled to the safe when necessary for the removal of the same.

With these and other objects in view, the invention consists in the construction and novel combination of parts hereinafter fully described, illustrated in the accompanying drawing and pointed out in the claims here-to appended; it being understood that various changes in the form, proportion, size and minor details of construction, within the scope of the claims, may be resorted to without departing from the spirit or sacrificing any of the advantages of the invention.

In the drawing:

Figure 1 is a side elevation of a safe hoisting device constructed in accordance with this invention and illustrating the manner of hoisting a safe from a sunken vessel.

Fig. 2 is an enlarged side elevation illustrating the construction of the coupling device and showing the normal arrangement of the same.

Fig. 3 is a central vertical sectional view of the same, the coupling member being shown at elevation.

Fig. 4 is a detail view of the weighted flexible loop or ring for engaging the coupling member.

Like numerals of reference designate corresponding parts in all the figures of the drawing.

In the accompanying drawing in which is illustrated the preferred embodiment of the invention, the safe-hoisting device comprises in its construction a coupling member 1 consisting of a straight body portion provided at its lower end with a substantially segmental head 2 and having an approximately semi-circular or segmental upper terminal portion 3 recessed at the lower edges at opposite sides of the stem or body portion to form recesses 4 and downwardly extending opposite engaging bills or flukes 5, which are adapted to be engaged by a loop or ring 6 of a salvage line 7. The lower segmental head 2 which projects from opposite sides of the stem or body portion to form upper shoulders 8 is provided with an eye 9 for the reception of the upper link of a short chain 10, which has its lower end linked into a loop 11 of a safe 12. The safe 12 which may be of any size or structure is designed to be arranged in a specially provided compartment 13 of a vessel 14. The compartment 13, which is designed to be arranged at the top of the vessel and to be clear of rigging or anything which might interfere with the removal of the safe 12, can be located in any such convenient position and the compartment is provided at the top with hinged doors 15 adapted to be opened automatically by the lifting of the safe and maintained normally in a closed position by the device for the removal of the safe. Access to the safe is designed to be had from the interior of the cabin or superstructure containing the said compartment 13 and the top hinged sections or doors 15 are maintained securely in a closed position by means of a bar or pin 16 extending through an opening 17 of the coupling member and arranged in recesses 18 of blocks 19 mounted on the hinged sections 15 at the free edges thereof as clearly shown in Fig. 3 of the drawing. The pin 16, which extends from opposite sides of the coupling member, may be secured to the same in any suitable

manner and by being arranged in the recesses of the blocks 19 the doors or closures of the compartment or portion thereof above the safe are securely maintained in a closed position. The loop into which the chain is linked may be secured to the safe in any desired manner.

The coupling member is provided at the upper enlarged end with an upwardly tapered guide consisting of inclined rods 20 and a central vertical rod 21 and carrying a ring or eye 22 at the apex for the attachment of a guide line 23 having slight knots or enlargements 24 at spaced points for indicating the depth or amount of line paid out and connected at its upper or outer free end with a buoy or buoyant marking device 25.

Access is had to the safe from the interior of the vessel under ordinary conditions and the buoyant marking device or buoy with the guide line 23 attached is designed to be arranged upon the vessel 14 in convenient position with relation to the safe compartment so that in event of the sinking of the vessel 14 the buoy will float off with the guide line and indicate the place of the sunken vessel.

When it is desired to remove the safe from the sunken vessel the buoy is taken up by a wrecking or salvage ship 26 and the salvage lines 7 with the flexible weighted loop or ring 6 are lowered to the coupling member, the guide line 23 being passed through the loop or ring 6, which is guided to the coupling member and is engaged with one of the hooks or projections 5 thereof by drawing it upward slightly when the weighted loop or ring has reached the top of the compartment 13. The loop or ring 6 will then be drawn into one of the recesses 4 and will be confined therein by a pivoted latch 27 hinged at 28 and adapted to swing upwardly from a horizontal position. Any suitable means may be employed for limiting the downward swing of the latch. In the construction illustrated in the accompanying drawing the heels 29 of the latches are arranged to engage the bills or flukes 5, but any other suitable construction may of course be employed. The flexible ring or loop 6, which is designed to be constructed of hemp or other suitable material wrapped with lead to secure the desired weight, is adapted to lengthen or elongate to enable a second loop or ring to readily pass over it should the same become necessary. This will enable one or more salvage lines to be connected with the coupling member and the tapered guiding device formed by the inclined rods 20 will cause the loop or ring to engage with one or the other of the said bills or engaging portions 5. The salvage or wrecking ship 26 is designed to be provided with a suitable crane or hoisting device 30 for lifting the safe from the sunken

vessel to the surface and placing it aboard the vessel 26. The hinged doors or closures 15 are adapted to open automatically when the safe 12 is lifted from the compartment 13.

Various forms of buoyant marking devices or buoys may be employed but it is preferable to use the marking device shown and described in a companion application executed by me of even date herewith and partially illustrated in the accompanying drawing.

The hinged doors are maintained closed by the lateral projections of the coupling member and they support the coupling member in a projecting position to enable the loop or ring of the salvage lines to be readily connected with the engaging portions of the said coupling member.

What is claimed is:

1. In a device for hoisting safes from sunken vessels, the combination with a vessel provided with a compartment open at the top and provided thereat with means for covering or closing the compartment, said means being adapted to open outwardly, and a safe located within the said compartment, of a coupling member extending from the compartment and connected with the safe, a guide line adapted to be coiled on the vessel and connected at one end with the said coupling device, and a buoyant marking device connected with the other end of the guide line.

2. In a device for hoisting safes from sunken vessels, the combination with a vessel provided with a compartment and having hinged doors arranged at the top of the compartment and opening outwardly, and a safe arranged within the compartment below the said doors, of a coupling member projecting exteriorly of the said doors and having engaging means, means connecting the coupling member with the safe, a guide line attached to the coupling member and extending therefrom for guiding a salvage line to the engaging portions of the coupling member, and a buoy connected with the guide line.

3. In a device of the class described, the combination with a vessel having a compartment provided at the top with doors, and a safe located within the said compartment, of a coupling member extending between the doors and maintained by the said doors in a projecting position, means for connecting the coupling member with the safe, means carried by the coupling member and resting upon the doors for holding the latter closed and also for supporting the coupling device, a guide line connected with the coupling device, and a buoyant marking device secured to the line.

4. A device of the class described including a coupling member provided at the top with depending bills or flukes and having

an upwardly projecting tapering guide consisting of inclined rods connected with and extending upwardly from the outer portions of the flukes, a guide line attached to the said guide, and a buoy secured to the line.

5. In a device of the class described, the combination with a vessel having a compartment provided at the top with hinged doors, said doors being provided at their meeting edges with blocks having opposite recesses, and a safe located within the compartment, of a coupling member extending between the meeting edges of the doors and provided with lateral projections resting in

the recesses of the said blocks, means for connecting the lower end of the coupling member with the safe, said coupling member being provided at the top with an engaging portion and a line connected with the coupling member for guiding the loop or ring of a salvage line to the engaging portion of the coupling member.

In testimony whereof I affix my signature in presence of two witnesses.

HENRY LOTZ.
